UNITED STATES PATENT OFFICE.

CHARLES H. BOMBARDIE, OF SOUTH BEND, INDIANA, ASSIGNOR TO WIREBOUNDS PATENTS COMPANY, OF KITTERY, MAINE, A CORPORATION OF MAINE.

WIRE-BOUND BOX.

1,364,850.

Specification of Letters Patent.

Patented Jan. 4, 1921.

Application filed February 20, 1917. Serial No. 149,923.

To all whom it may concern:

Be it known that I, CHARLES H. BOMBARDIE, a citizen of the United States, and a resident of South Bend, county of St. Joseph, and State of Indiana, have invented 5 Improvements in Wire-Bound Boxes, of which the following description, in connection with the accompanying drawings, is a specification, like characters on the drawings representing like parts.

This invention relates to boxes of the wirebound type, and the purpose is to provide such a box which will be neat, more durable than those hitherto known, and at 15 the same time less expensive to construct.

My invention will be best understood by reference to the following description taken in connection with the accompanying drawings, wherein:

20 Figure 1 is a perspective view of a wirebound box embodying my invention;

Fig. 2 is a plan view of one element of the separable fastening device used in constructing the box shown in Fig. 1;

25 Fig. 3 is an edge view thereof;

Figs. 4 and 5 are similar views of the co-operating element of the fastening device;

Fig. 6 is a side elevation showing the first 30 step of applying one of these elements to a binding wire;

Fig. 7 shows the element in position; and

Fig. 8 is a side view showing the closure of the box.

In accordance with my invention I construct 35 a wirebound box similar in general characteristics to those well known in the art and described in reissue Letters Patent to

Inwood and Lavenberg No. 12,725, November 26, 1907. Referring to Fig. 1 such a box

40 comprises side sections each of which includes cleats 3 and side material such as sheets of veneer 5 secured together in co-operative foldable relationship by universally flexible binding wires 7 secured by staples 9

45 extending through the side sheets 5 into the cleats 3. Suitable end pieces 11 are provided. The continuity of the wire binding is broken in one or more places and I have here shown it as broken in two places, one

50 at each upper corner of the box, to provide a removable cover. Suitable means are provided for connecting the wire ends to complete the continuity of the bindings and so close the box to form a shipping receptacle.

In accordance with my invention I construct 55 the box blanks with the wires 7 terminating adjacent the edges of the sides as shown in Fig. 6. I further provide separable fastening devices easily engaged with the ends of the wires and which may be secured 60 together to tension the wires about the box and press the sides of the same together at the corners, which will form a neat finish, and which may be repeatedly opened and closed.

In the embodiment of my invention illustrated 65 in the accompanying drawings, I provide two co-operating members one for engagement with each of a pair of opposed wire ends and adapted to be locked together 70 to complete the continuity of the binding. Referring to Figs. 2 and 3, where I have shown a suitable form for one of these elements, it will be seen that it comprises a 75 sheet metal plate 13 formed at one end as a portion of a separable fastening, for example by having an eye 15 formed therein for engagement with a hook portion on a co-operating member. To secure the plate 13 to the wire, a transverse opening 17 is 80 formed therein, herein a hole slightly larger than the wire to which the plate is to be applied. Preferably I also provide an opening in the form of a laterally opening slot 19 defining a hook portion 21 at the end of 85 the member. The plate 13 may be embossed as shown at 23 to provide a recess to receive the end of the wire 7 in a manner which will be more easily understood from the explanation following.

Referring to Figs. 6 and 7, the member 13 is secured to the wire 7 by slipping it over the same with the wire passing through the hole 17. When the member is in the position shown in Fig. 6, it may move freely 95 along the wire. The member is next bent down in a clockwise direction and it is apparent that it will engage with the wire with a sharp bend or nip where the latter passes through the same and will thus be 100 locked to the wire against strain in the line thereof. When the member is bent down as described, it is preferably kept somewhat at an angle to the wire and after bending is 105 swung into line with the same so that the hook portion 21 will engage over the wire as shown in Fig. 7 with the latter entering the slot 19. This provides for a second bite

or nip in the wire which is, as shown in Fig. 7, interwoven with the plate 13. The end of the wire is positioned by being received in the embossed portion 23 and clamped between the plate 13 and the box side. It is thus held in the line of the body of the wire and it will be readily understood that this clamping of the wire end contributes to the security of the fastening formed by the interweaving of the wire with the plate. The principle last referred to will be recognized as that embodied in the knots known as a "midshipman's heaving" and as a "rolling hitch" which are secured as long as the spare end is held, although very lightly, in the line of strain.

It will be readily understood from an inspection of Figs. 6 and 7, that when the member 13 is applied to the wire 7, it acts to tension the same.

Referring to Figs. 4 and 5, I have shown a member 25 adapted to coöperate with the member 13. This member consists of a sheet metal plate having the transverse hole 27, laterally opening slot 29 forming the hook 31, and embossed recess 33 corresponding in all respects to the parts numbered 17, 19, 21 and 23, described in connection with the member 13. This member is applied to the wire end in the same way as is the member 13 and it differs therefrom only in the fact that the end 35 instead of being formed with an eye is made of such size as to enter the eye 15 of the member 13, and bend over in the form of a hook, as clearly shown in Fig. 8. The end 35 may, if desired, have a hole 37 therethrough in which a nail or similar lever member may be inserted to assist in reeving the end taut through the eye 15 and in bending it down.

It will be apparent from the description of the illustrative embodiment of the invention shown in the accompanying drawings, that a box equipped with these fasteners is very desirable. The fastening can be opened and closed many times without impairing the strength of the wire. The fastening devices are simple in form and are quickly applied and by their very application act to tension the wire bindings about the box, and after being placed in position or adjusted are easily secured together with any desired degree of tightness.

While I have described in detail the embodiment of my invention shown in the accompanying drawings, I have done so in

order that the reader might more readily comprehend that embodiment and not because the details referred to are essential. The structure may be widely varied without departing from the spirit of the invention, and what I do claim and desire to secure by Letters Patent, is:

1. In a wirebound box, a separable fastening means for connecting complementary binding wires on adjacent sections of the box, comprising a pair of coöperating interfastening members detachably secured on the wires in relative positions to tension the wires and bring the box sections closely together by the fastening of said members together.

2. In a wirebound box, means to close the box by detachably connecting the binding wires comprising a pair of members each adapted to grip a binding wire and be detachably connected to the other member whereby the box may be repeatedly opened and closed.

3. In a wirebound box having separably related adjacent sections, and complementary binding wires secured to said sections, means for separably tensionally connecting said wires comprising a pair of members each adapted to detachably engage and grip an end of a binding wire and to detachably engage with each other to complete the continuity of the wire binding and tension the same adjacent the point of connection.

4. Box fasteners for wirebound boxes comprising a pair of members, each adapted to detachably engage a binding wire and to detachably engage with each other.

5. A fastener for use in securing together sections of a wirebound box constructed and arranged to slip over the end of a binding wire and by bending become attached thereto and having means to engage with a similar fastener similarly secured to the wire of another section.

6. In a wirebound box, a separable fastening means for connecting complementary binding wires on adjacent sections of the box, comprising a pair of members each adapted to engage and grip a binding wire at a desired point thereon and to detachably engage the other member to connect and tension the binding wire.

In testimony whereof I have signed my name to this specification.

CHARLES H. BOMBARDIE,
